LOCKING GARMENT HANGER

Vincent Flocco, Newark, N. J.

Application May 28, 1935, Serial No. 23,841

4 Claims. (Cl. 223—85)

This invention relates, generally to garment hangers, and the invention has reference, more particularly, to a novel garment hanger having means for locking or positively retaining the same upon a supporting rod in use.

Garment hangers as heretofore constructed are very often accidentally disengaged from their supporting rods in use, especially when removing or replacing an adjoining garment, so that the disengaged garment hanger falls to the floor and the garment held thereby is usually soiled and wrinkled and sometimes damaged, as by being accidentally stepped upon.

The principal object of the present invention is to provide a novel garment hanger having easily operated means for locking or positively retaining the garment hanger upon its supporting rod and against accidental displacement therefrom, the said locking means being easily 20 and quickly released when it is desired to remove the hanger from the supporting rod.

Another object of the present invention lies in the provision of a novel locking garment hanger that is of simple, sturdy and inexpensive construction and which is reliable in use.

Other objects of this invention, not at this time more particularly enumerated, will be clearly understood from the following detailed description of the same.

The invention is clearly illustrated in the accompanying drawing, in which:

Fig. 1 is a fragmentary view of the novel garment hanger of this invention employed for supporting a garment, the user being shown in the act of applying the locking or retaining means for preventing the accidental dislodgment of the hanger from its supporting rod.

Fig. 2 is an enlarged view of a portion of the structure of Fig. 1.

Fig. 3 is a view similar to Fig. 2 but shows the locking means applied, and also illustrates in dotted lines how the locking means prevents the falling of the hanger.

Fig. 4 is a fragmentary perspective view illustrating the manner of releasing the locking or retaining means preparatory to removing the hanger from its supporting rod.

Fig. 5 is a fragmentary side view of the hanger hooks and locking means therefor, and

Fig. 6 is an enlarged sectional view taken along line 6—6 of Fig. 5.

Similar characters of reference are employed in said views, to indicate corresponding parts.

Referring now to the said drawing, the reference numeral 1 designates the novel garment

hanger as a whole, the said hanger having the usual bow shaped garment supporting bar 2 and upstanding hook 3 with its shank 4 extending through and attached to the bar 2.

According to the preferred construction, the free end of the hook 3 is apertured at 5 or otherwise formed for receiving and retaining one end of a short chain or flexible connector 6, to the other end of which is attached a locking member or clasp 7 of approximately C-shape as viewed in plan (see Fig. 6). The locking member or clasp 7 is shown as provided with an aperture 8 for receiving the end link of chain 6 to thereby attach the clasp to the chain 6. Aperture 8 is positioned on the central imaginary axis 13 or centerline 13 of clasp 7, the said axis 13 passing through the center of the substantially circular central receiving aperture 9 of the clasp and midway through the throat or space 10 separating the opposed ends of clasp arms 11. 20

The width of throat 10 is somewhat less than the diameter of the shank 4 of hook 3. The upper portion of shank 4 is squeezed inwardly from both sides or pinched from opposite sides at 12, thereby providing a narrow or constricted portion 12 positioned to extend at right angles to the plane of hook 3, the said constricted portion 12 being of substantially rectangular cross-section as shown in Fig. 6. The constricted portion 12 is of slightly less thickness than that of throat 10, whereas the width of this constricted portion, i. e. the length of its rectangular cross-section, is somewhat greater than the diameter of shank 4 (see Fig. 6). 25

By holding locking clasp 7 with its imaginary axis or centerline 13 at right angles to the plane of hook 3, as shown in Figs. 1, 2 and 6, the clasp 7 may be moved toward the shank 4, the constricted portion 12 passing through throat 10 and into the central receiving aperture 9. The outer edges of arms 11 are preferably rounded or beveled at 14 to facilitate the entrance of constricted portion 12 into throat 10. If the clasp 7 is now released it will slide down the shank 4 but will not come off of this shank since throat 10 is of less width than the diameter of shank 4, as illustrated in full lines in Fig. 3, wherein the hook 3 is shown supported on the rod 15. 35

The garment hanger 1 is now locked on the supporting rod 2 and cannot be accidentally removed 50 therefrom. For example, if the garment hanger is pushed into the dotted line position shown in Fig. 3, as often happens when inserting or removing an adjacent garment, the chain 6 prevents 55

the garment hanger from falling from the rod 15. This will be evident when it is noted that though clasp 7 has moved up to the constricted portion 12, yet since the larger dimension or 5 width of this constricted portion extends parallel to the rod 15, i. e. at right angles to the plane of hook 3, and as this larger dimension of the constricted portion is now presented toward the throat 10, it is impossible for the clasp 7 to disengage the shank 4, the width of the constricted portion 12 being considerably greater than that of throat 10.

When it is desired to remove the garment hanger from the supporting rod 15 it is merely 15 necessary to press or move a finger, for example the forefinger 16 of the right hand, against the chain 6, pressure being applied in a direction parallel to rod 15, i. e. at right angles to the plane of hook 3. This motion of the finger first causes 20 clasp 7 to turn on shank 4 so that the axis 13 of this clasp lies in substantially the same plane as the long axis of constricted portion 12. Continued finger pressure on chain 6 causes clasp 25 7 to slide up shank 4 until the throat 10 arrives opposite the constricted portion 12, whereupon the clasp 7 passes off of the shank 4 as shown in Fig. 4. In practice, a quick snap of the finger in the proper direction, i. e. at right angles to the plane of hook 3 serves to remove the clasp 7 from 30 shank 4, whereupon the hanger 1 may be taken off of rod 15. No amount of rough handling of the hanger 1 while the same is on rod 2, however, will release clasp 7, it being necessary to apply a force to chain 6 in a direction parallel to rod 35 15 in order to unlock clasp 7.

As many changes could be made in the above construction and many apparently widely different embodiments of this invention could be made without departing from the scope thereof, as defined by the following claims, it is intended that 40 all matter contained in the above description or shown in the accompanying drawing shall be interpreted as illustrative and not in a limiting sense.

45 I claim:

1. A garment hanger comprising, a garment supporting bar, a hook having a shank portion attached to said bar for supporting the latter, a substantially C-shaped clasp having an open 50 mouth, a flexible connector having one end thereof attached to the free end of said hook and its other end attached to said clasp, said clasp being arranged to receive the shank of said hook through the open mouth thereof, to thereby re-

55 tain said hanger upon a support and against accidental displacement.

2. A garment hanger comprising, a garment supporting bar, a hook having a shank portion attached to said bar for supporting the latter, a clasp having a receiving recess provided with an entrance throat, a flexible connector having one end thereof attached to the free end of said hook and its other end attached to said clasp, said hook shank having a constricted portion extending at an angle to the plane of said hook, said clasp throat being slightly larger than said shank constricted portion, whereby the latter may be entered through said clasp throat so that said hook shank is received within said clasp receiving recess, said hook and said flexible connector thereby forming a closed member for encircling a supporting rod.

3. A garment hanger comprising, a garment supporting bar, a hook having a shank portion attached to said bar for supporting the latter, a clasp having a receiving recess provided with an entrance throat, a flexible connector having one end thereof attached to the free end of said hook and its other end attached to said clasp at a point opposite said throat, said hook shank having a constricted portion of substantially rectangular cross-section, the long axis of said restricted portion extending substantially at right angles to the plane of said hook, said clasp throat being slightly larger than the short axis of said shank restricted portion, whereby the latter may be entered through said clasp throat so that said hook shank is received within said clasp receiving recess to thereby lock said garment hanger upon a supporting rod, the application of finger pressure to said flexible connector in a direction at right angles to the plane of said hook serving to release said clasp from said hook shank.

4. A garment hanger comprising a garment supporting bar, a hook attached to said bar for supporting the latter, said hook having a constricted portion formed by pinching inwardly from opposite sides, said constricted portion having a short dimension and a long dimension, the long dimension extending at an angle to the plane of said hook, a chain having one end attached to the free end of said hook, and a clasp attached to the other end of said chain, said clasp having a receiving recess provided with an entrance throat of larger size than the short dimension of said constricted portions but of lesser size than the long dimension of said constricted portion.
